COLUMBIA, A FIRM.

HAND-STAMP.

SPECIFICATION forming part of Letters Patent No. 774,675, dated November 8, 1904.

Application filed March 26, 1904. Serial No. 200,181. (No model.)

To all whom it may concern:

Be it known that I, HENRY M. KENDRICK, a citizen of the United States, residing at Washington, in the District of Columbia, 5 have invented a new and useful Hand-Stamp, of which the following is a specification.

This invention relates generally to hand-stamps, and particularly to that class made entirely of rubber.

10 The object of the invention is in a novel and practical manner to cushion the head independently of the handle, thus to cause the printing-face of the stamp to strike squarely on the article to be imprinted, insuring thereby a perfect imprint even when the printing-face is struck upon the article at an angle thereto; furthermore, to limit the degree of compression of the head without jar to the hand of the user, thereby preventing any 15 blurred appearance of the imprinted characters due to excessive lateral expansion of the head; furthermore, to permit removal of the head from the handle and the attachment of a new head, thus effecting a saving in the use 20 of the stamp; furthermore, to permit adjustment of the date-type to cause them to occupy the same plane as the other types on the head, and, finally, to improve and render more efficient hand-stamps of the character 25 stated.

With the above and other objects in view, as will appear as the nature of the invention is better understood, the same consists in the novel construction and combination of parts 30 of a hand-stamp as will be hereinafter fully described and claimed.

In the accompanying drawings, forming a part of this specification, and in which like characters of reference indicate corresponding parts, there are illustrated three forms of embodiment of the invention, it being understood that the elements therein exhibited may be varied or changed as to shape, proportion, and exact manner of assemblage without departing from the spirit thereof.

In the drawings, Figure 1 is a view in per-

spective exhibiting the parts of the stamp separated. Fig. 2 is a view in vertical section of a portion of the stamp shown in Fig. 1. Fig. 3 is a sectional detail view showing a means for adjusting the date-type with reference to the face of the head. Fig. 4 is a sectional detail view showing a slightly-modified form of the stamp.

Referring to the drawings, 1 designates the handle, which may be of the usual shape shown and provided at its lower end with an enlarged base 2, formed within a chamber 3, which is herein shown as approximately cone-shaped in cross-section; but it will be understood that it may be of any other shape desired and still be within the scope of the invention. The lower edge of the face is provided with a circumferential flange 4, which is by preference approximately dovetail shaped and is designed to engage a similarly-shaped groove 5, formed in the upper face of the head 6, the head being provided with a boss 7, which constitutes an air-compressing element, the boss being herein shown as approximately cone-shaped; but it may be otherwise contoured, if desired. The head is further provided with a marginal flange 8, which is adapted to inclose the outer side of the lower portion of the base, as clearly shown in Fig. 2, and thus reinforce the latter against lateral yielding or spreading. The head is assembled with the base by a suitable cement, which is interposed between the flange 8 at the base and between the lower end of the base and the head and is also filled into the groove 5. When the cement hardens, the chamber 3 is hermetically sealed and under the impact transmitted to the head in use of the stamp the boss 7 will operate to compress the air between its outer walls and the inner walls of the chamber, and thus the air is caused to present an effective cushion, which will not only in a large measure remove all jar from the hand of the operator, but will also limit the compression of the head. Moreover, the pneumatic cushion presented will allow the head to yield readily, so

that the characters carried thereby always flatly impinge the object to be imprinted even though the head be struck at an angle thereto. By making the head and handle in two parts the former may be removed and replaced by a new one in case of damage, and thus effect a saving in the use of the device. The under face of the head is provided with the usual date-type socket 9, in which the date-type are held in any preferred manner, and as these form no part of the present invention illustration thereof is omitted.

In some cases there might be a difference in the height of the printing-type and the date-type, and in order to cause all of the printing characters to occupy the same plane the device shown in Fig. 3 is employed to adjust the date-type and consists of a plate 10, which is of the size to fit within the date-type socket, and through this plate projects a screw 11, having a shoulder 12, that bears against the inner face of the plate, the head of the screw being flush with the outer face of the plate. This screw engages a nut 13, which is embedded in the boss 7, and it is therefore yieldable, so that when the plate is moved away from the inner wall of the socket the plate will yield to impacts through its connection with the screw 11, and thus prevent injury to the date-type, which might otherwise occur if the plate were rigid and non-yielding in character. It will be seen that when the screw is turned to the left the plate will be moved outward, owing to the contact between it and the shoulder 12, and that when the screw is turned to the right the plate will be seated against the under wall of the type-socket. The head is provided with the usual depending flange 14 to hold the printing-type against lateral displacement in use. Instead of making the head and handle in two parts, as above described, they may be made integral, as shown in Fig. 4, wherein the air-chamber 15 is of the same general contour as that shown in Fig. 2, although it may be otherwise shaped and still be within the scope of the invention.

The device of this invention is exceedingly simple of construction and will be found thoroughly effective and durable in use for the purpose designed. By the employment of the pneumatic chamber all jar is absorbed, so that in use the operator's hand will not become weary, as frequently happens with the ordinary form of hand-stamps.

Having thus fully described my invention, what I claim is—

1. A hand-stamp embodying a handle and a head centrally disconnected therefrom, a hermetically-sealed air-chamber interposed between the parts, and means for causing the yield of the head to be equal from center to circumference.

2. A hand-stamp embodying a handle, an

inherently-elastic head centrally disconnected therefrom, and means for causing the yield of the head to be equal from center to circumference.

3. A hand-stamp comprising a handle and a head, one of the members having a hermetically-sealed air-chamber and the other an air-compressing element disposed within the chamber.

4. A hand-stamp comprising a handle having a hermetically-sealed air-chamber and a head having an air-compressing element disposed within the chamber.

5. In a hand-stamp, a head having a date-type-receiving socket, and yieldable means disposed within the socket to adjust the type.

6. In a hand-stamp, a head having a date-type-receiving socket, and a yieldable type-adjusting plate disposed within the socket.

7. In a hand-stamp, a head having a date-type-receiving socket, a type-adjusting plate, and a screw and nut for adjusting the plate, one of which latter elements is yieldable with the plate.

8. In a hand-stamp, a head having a date-type-receiving socket, and yieldable means disposed within the socket, and accessible from the face of the head, for varying the operative plane of the date-type.

9. A hand-stamp comprising a handle having a hermetically-sealed air-chamber, a head having an air-compressing element disposed within the chamber and provided in its operative face with a date-type-receiving socket, and a screw and nut for adjusting the plate, one of said latter elements being housed within the compressing element.

10. A hand-stamp comprising a handle having a hermetically-sealed air-chamber, a head having an air-compressing element disposed within the chamber and provided in its operative face with a date-type-receiving socket, a nut housed within the compressing element, a plate disposed within the socket, and an adjusting-screw passing through the plate and engaging the nut.

11. A hand-stamp comprising a handle having a hermetically-sealed air-chamber, and a head having an air-compressing element disposed within the chamber and provided with lateral reinforcing means.

12. A hand-stamp having a pneumatically-cushioned head, means for limiting the compression of the head, and a marginal flange for reinforcing the same against lateral tension.

13. A hand-stamp comprising a handle provided with a chamber and with a depending flange, and a head provided with an air-compressing boss disposed within the chamber, with a groove to receive the flange of the handle, and with a marginal flange to bear against the outer side of the chamber.

14. A hand-stamp having a head provided with a date-type-receiving socket, a nut mounted within the head, a screw engaging the nut and provided with a shoulder, and a plate 5 mounted within the socket and bearing against the shoulder.

In testimony that I claim the foregoing as

my own I have hereto affixed my signature in the presence of two witnesses.

HENRY M. KENDRICK.
